R. PERL

SLEEPING BAG DEVICE

Filed August 18, 1925

FIG. 1.

FIG. 2.

FIG. 3.

FIG. 4.

ROSE PERL
INVENTOR:

By her Attorney

Fredrik Bentefeld

Patented May 4, 1926.

UNITED STATES PATENT OFFICE.

ROSE PERL, OF NEW YORK, N. Y.

SLEEPING-BAG DEVICE.

Application filed August 18, 1925. Serial No. 50,905.

To all whom it may concern:

Be it known that I, ROSE PERL, subject of Rumania, residing at county of Kings, New York city, State of New York, have invented new and useful Improvements in a Sleeping-Bag Device, of which the following is a specification.

My present invention relates to a device of a sleeping bag nature, designed primarily for infants.

It is an object of the invention to provide a device whose use and purpose is comparable to that of a sleeping bag, designed primarily to provide a bedding device for infants, whereby an infant may be expeditiously and suitably supported, covered and firmly tucked in.

An object of the invention lies in providing a device of this character which will permit the infant to be deposited or removed at will from a place of rest such as a baby-carriage or bassinet, or carried about, without disturbing or in any way altering the tucked in position of the infant.

Another object lies in providing a device of this character which embodies in itself the necessary padding and warmth essential to an underlying support for the infant and to a cover therefor, together with the desired bedding material, such as sheets.

One feature of the invention lies in providing this device in the form of a single normally unfolded member which may be folded on itself for the purpose of providing a mattress portion and a cover portion.

Another object of the invention is to provide a device of this character which will be of extremely simple construction, inexpensive to manufacture, presenting a neat outward appearance, and embodying no complicated parts or devices which would require special skill in manipulation or become a possible source of annoyance. Another object is to render this device clean and sanitary, and adaptable to easy and thorough airing and cleaning.

According to another feature of the invention, means are provided in attachment with or integral with the single member referred to, for retaining the device in operative or folded over position, and readily and easily adjustable for the purpose of expeditiously and quickly allowing the device to be opened up into unfolded position.

Another feature of the invention lies in providing lateral extensions or flaps which

are automatically brought into positions overlying the edges of the folded over portions, thereby sealing the sides of the closed device when the fastening means are manipulated for securing the device in operative position.

In a preferred construction the member constituting the body of the device is elongated and is substantially rectangular, having one end semicircularly curved for the purpose of providing a head-rest for the infant. The elongated member is padded in a suitable manner to give it sufficient body, softness, and warmth, for its designated purposes.

In a preferred construction, lateral or side extensions are provided along opposite edges of an intermediate portion, and fastening means are carried by these extensions and preferably comprise spaced sets of elongated binding elements such as ribbons or strings, whereby the latter may be engageable over an adjacent portion of the member which has been brought into a position overlying the intermediate portion, and whereby the extensions will seal the openings between the overlying portions to form a substantially closed receptacle in the nature of a sleeping bag.

The invention contemplates providing bed sheet material, either of ordinary fabric, or of rubber, or both, in association with the device whereby suitable material may underlie and overlie the infant.

In a preferred type of construction, the elongated member heretofore referred to is composed of two elements: an inner padding element, in the nature of a very soft mattress or elongated pillow, and an outer cover element snugly enclosing the entire inner element and preferably removable therefrom. In a preferred embodiment, the outer cover element comprises a tubular and suitably shaped casing, and is provided with an opening for removably receiving the inner padded or stuffed element therethrough. This opening is preferably provided along a transverse line adjacent to the rectangular end of the casing, and on that side which will be concealed when the device is folded on itself.

Suitable ornamentation such as edging of lace or other material, may be provided as desired, but forms no essential part of the invention.

For the attainment of the foregoing ob-

jects, and such other objects as may herein-after appear or be pointed out, I have illustrated a preferred form of my device, embodying the various features of the invention, in the accompanying drawings, in which

Fig. 1 is a perspective view of the entire device, as viewed from above, in opened position;

10 Fig. 2 is a similar view, showing the device in operative position;

Fig. 3 is a cross-section taken along the line 3—3 of Fig. 2, and

15 Fig. 4 is a fragmentary perspective view of a portion of the device, showing a modification.

Referring to the drawings, it will be apparent that the device comprises preferably an elongated substantially rectangular member 10 having a rectangular end 11 and a semi-circular end 12. The member 10 is preferably of a width suitable to receive an infant longitudinally thereof, but it will be understood that the width may be varied to suit requirements, as for example, where two infants may be laid side by side. The length of the device is preferably such that it may be folded on itself along a transverse line so that the rectangular end 11 may be brought to overlie the base of the semi-circular end 12 to constitute an enclosed or sleeping bag portion of a length approximately the length of an infant from its feet to its neck, that is, in the nature of 2 ft.

35 Side extensions or flaps 13 are carried along opposite edges of an intermediate portion of the member 10, and extend from approximately the base of the semi-circular head-rest portion 12 to substantially the mid-portion of the entire member, and are of a suitable width, preferably equal to approximately the thickness of the padded member 10. At their outer edges, the flaps 13 carry elongated binding elements or ribbons 14, suitably spaced and aligned with each other to form spaced sets of ribbons. The latter are of a length suitable to engage over the overlying adjacent portion of the member 10, as shown in Fig. 2, whereby they may be bound together, as by tying, in a manner which will be obvious. In the particular construction illustrated, I have shown three binding ribbons 14 on each side, but it will be obvious that this number may be varied at will to suit requirements; and that the binding elements may be provided with fastening devices such as buckles, or the like, so that the elements may be engaged or bound together in a manner other than tying.

60 In this connection, reference to Fig. 4 will show one modification of the fastening means wherein loops or straps 15 are provided at spaced intervals along the opposite edges of the overlying portion of the member 10, the spacing being such that the straps 15

may be made to register with the elements 14, so that the latter may be threaded through the straps 15 before being bound together. This modification illustrates one of several expedients which are contemplated for increasing the security with which the device is retained in closed position.

70 In accordance with the preferred construction illustrated in the drawings, the member 10 is constituted of two elements: 75 an inner element 16 (see Fig. 3) and an outer cover 17 therefor. The element 16 is preferably padded or stuffed, and comprises an elongated mattress or pillow of the same configuration as the entire device, and 80 of a thickness and composition whereby sufficient softness and warmth is combined with great flexibility. The outer element 17 comprises a casing of a shape to enclose the inner element snugly, and is constituted preferably of two overlying and marginally attached sheets, a bottom sheet 18 and a top sheet 19. In this construction, the flaps 13 are preferably attached to the casing element 17 by stitching along the marginal attachment between the top and bottom sheets 18 and 19. The casing element 17 is preferably provided with an opening 20 for removably receiving the inner element 16 therethrough. The opening 20 comprises a transverse slit, 95 and means, such as buttons 21, are provided for normally retaining the edges of the slit together. The slit is preferably positioned along a transverse line adjacent to, but not at, the rectangular end 11 of the 100 member 10. It is preferable also to provide the slit in the top sheet 19, so that it will be totally concealed when the member 10 is folded on itself.

105 Suitable marginal ornamentation, such as the lace 22, may if desired be attached to portions of the device, as for example, around the semi-circular end 12, and around the edges of the flaps 13.

110 It will be obvious from what has gone before that an infant may be laid upon the device when the latter is open as in Fig. 1, the infant's head resting upon the semi-circular end portion; the bottom portion of the member 10 may then be folded over to constitute a cover portion for the infant, as shown in Fig. 2, and the sets of binding elements 14 may then be engaged thereover and bound together to firmly engage spaced portions of the overlying cover portion, whereby the device will be retained in folded over position. It will be observed that the flaps 13 will be drawn up over the edges of the overlying portions when the binding elements 14 are bound together, whereby the openings between the overlying portions will be effectually sealed. As a result, a device simulating a sleeping bag will be produced wherein the infant has a comfortable mattress portion underneath him, and a soft and 115 120 125 130

warm cover portion overlying him, the whole being completely air-tight by virtue of the side flaps 13. It will be further observed that suitable auxiliary devices such as the straps 15, will serve to prevent the possible movement and kicking of the infant from dislodging the cover portion.

5 In the preferred construction illustrated, the infant will recline upon bed sheet material, and will have similar material overlying it; and if preferred, any desired portion of the casing element 17 may be made of rubber; or a separate rubber element (not shown) may be associated with the device

10 in a suitable manner.

The position of the slit 20 has been determined by experiment to be such as will least interfere with comfort and neat appearance.

15 The removability of the outer casing element 17, together with the fact that the member 10 is normally flat and may be opened up, renders the device extremely efficient from the standpoint of cleanliness and sanitation. It will be observed that the entire device may be expeditiously opened in almost an instant by merely untying the binding elements 14; and when opened, the opportunities for airing, or for ready re-

moval and substitution of an outer casing 30 element 17, are such as will be apparent.

It will be obvious that the device may be adapted for use by adults, although its primary purpose is for infants' use.

10 Various changes may be made in the details herein described and illustrated for the purpose of explaining the nature of my invention by those skilled in the art without departing from the spirit and scope of the appended claim, and it is therefore intended 40 that these details shall be interpreted as illustrative and not in a limiting sense.

I claim:—

A sleeping bag comprising an elongated casing for a foldable padded element, said 45 casing comprising a tubular element having an opening to removably receive said padded element therethrough, having non-tubular side extensions carried by an intermediate portion thereof, and being provided with 50 binding elements along the edges of said extensions, a pillow-like device filling said casing, the said casing and pillow-like device being foldable intermediate the ends thereof to form mattress and cover por- 55 tions.

In testimony whereof I affix my signature.

ROSE PERL.
